UNITED STATES PATENT OFFICE

HUBERT G. JOHANNES, OF CHIPPEWA FALLS, WISCONSIN, ASSIGNOR TO ALBERT PICK-BARTH COMPANY, INC., OF CHICAGO, ILLINOIS, A CORPORATION OF NEW YORK

DESIGN FOR A MIXING SPOON

Application filed November 1, 1930. Serial No. 37,497. Term of patent 14 years.

To all whom it may concern:

Be it known that I, HUBERT G. JOHANNES, a citizen of the United States, residing at Chippewa Falls, in the county of Chippewa and State of Wisconsin, have invented a new, original, and ornamental Design for Mixing Spoons, of which the following is a specification, reference being had to the accompanying drawings, forming a part thereof.

In the drawings: Fig. 1 is a perspective of a mixing spoon embodying the invention, Fig. 2 is a side view of the spoon.

I claim:

The ornamental design for a mixing spoon as shown.

HUBERT G. JOHANNES.
